UNITED STATES PATENT OFFICE.

JOHN SUTTON, OF NEW YORK, N. Y., ASSIGNOR TO HIMSELF AND DE WITT C. VAN TUYL,
OF SAME PLACE.

CONDENSING STEAM-ENGINE.

Specification of Letters Patent No. 24,246, dated May 31, 1859.

To all whom it may concern:

Be it known that I, JOHN SUTTON, of the city, county, and State of New York, have invented certain new and useful Improvements in Condensing Steam-Engines; and I do hereby declare that the following is a full, clear, and exact description of the same, reference being had to the accompanying drawing, forming part of this specification, in which—

Figure 1, represents a sectional elevation of an engine with my improvements applied, taken in a plane parallel with the plane of revolution of the crank. Fig. 2, is a sectional elevation of the same, in a plane parallel with the axis of the crank shaft.

To enable others skilled in the art to make and use my invention, I will proceed to describe its construction and operation.

The engine represented in the drawing as having the invention applied is of the kind known as the beam engine, that form of engine serving as well as any other to illustrate its application to use. The cylinder A, may have any kind of valve or system of valves for the induction and eduction of steam, the slide valve B, being represented as the simplest means for the purpose. The valve or valves may be operated by the usual eccentric C, on the crank shaft D; and the connection of the crank E, and piston F, with the beam G may be by the usual connecting rod H, and piston rod I.

J, is the air pump, which is also the condenser, fitted with a tight piston K, whose attached rod K¹, works through a stuffing box in its cover J¹, and provided on one side with a valve chest L, to which is connected the eduction pipe a, from the cylinder A, the said chest being fitted with a slide valve b, by which two passages c, c¹, leading to opposite ends of the air pump may be alternately opened and closed. At the lower end of the air pump there is a passage f¹, communicating through a foot valve g¹, with the hot well M, which, for convenience is arranged below the air pump; and at the upper end of the air pump there is a passage f, which passes partly around the air-pump cylinder and communicates through a foot valve g, with the hot well. These passages f, f¹, are entirely separate from each other. The cover J¹, of the air pump and the sole plate J², are both made hollow to receive the cold water for the con-

densing of steam and both are perforated with numerous small holes to let the injection water into the pump in showers.

The cavities in the cover J¹, and the sole plate J², are supplied alternately at proper intervals with cold water by two pipes d¹, d², branching from the main injection pipe d, which is fitted at the junction of the branches with a cock or valve e, of such character as to permit the water to be directed through either of the branch pipes d¹, d², but not through both at the same time. The branch pipe d¹, where it passes through the hot well, and the plate J², should be incased to protect them from the heat of the water and vapor that is contained in the hot well below the mouth of the waste pipe h.

The valve b, of the air-pump is connected with the arm i, of a rock shaft N, which derives motion from the eccentric C¹, and which constitutes a portion of the gear for working the valve B, of the cylinder A. The construction of the slide valve b, and arrangement of the ports of the valve chest L, are such that the valve will just cover both ports and commence opening either one immediately after it has closed the other; and the relative arrangement of the connections of the two valves B, and b, is such that the valve b, commences to open the one port c, of the air pump just as the valve B, commences opening the lower port of the cylinder to the eduction pipe a, and the other port c¹, just as the valve B, commences opening the upper cylinder port to the eduction pipe a. The drawing represents the connections of the said valves B, and b, so arranged that the lower air pump port c¹, opens as the lower cylinder port opens to the eduction pipe, and the upper air-pump port c, opens as the upper cylinder port opens to the eduction pipe, but the arrangement may be precisely the reverse.

The injection cock e, is connected by a rod u, with an arm v, on a rock shaft l, which derives motion from the air pump piston K, in the manner to be hereinafter described, to open the branches d, d¹, alternately, the branch leading to either end of the air pump being opened while its piston is moving toward the opposite end.

The operation of the air pump by the pressure of the exhaust steam is as follows. The air pump piston, at the time of the commencement of the opening of either port

of the cylinder to the eduction pipe, as the steam piston arrives at or near either end of its stroke, is stationary near one end of the air pump with a vacuum on both sides of it, the vacuum being produced as will be presently explained, and the weight of the piston being balanced by the weight of the mechanism to be hereinafter described, by which it is made to help the crank past the centers, or by other suitable means. Suppose for example the steam piston to be just completing its upward stroke, as represented in the drawing, the air pump piston would then be at the lower end of the pump with a more or less perfect vacuum above and below, and the branch d^1 , of the injection pipe would be injecting cold water into the pump above its piston; but as soon as the opening of the lower end of the cylinder to the eduction pipe, and the simultaneous opening of the lower port c^1 , of the air pump, commence, the exhaust steam entering the air pump below its piston forces the latter upward and so discharges the water which has collected above it into the passage f , from whence it passes through the foot valve g , to the hot well. The pressure of the steam below the piston also drives out through the valve g^1 , what water may have been previously in the passage f^1 . The stroke of the air pump is completed while the steam piston completes its ascent and descends only a very short distance, and the upper branch d^1 , of the injection pipe is closed at an early period in the stroke of the air pump, and the lower branch d^2 , is opened before the stroke is completed, and continues open during the whole remaining portion of the stroke of the steam piston, so that the said piston has or may have a vacuum produced below it throughout all but a very short portion of its stroke at the commencement thereof.

When the opening of the upper end of the steam cylinder to the eduction pipe and simultaneous opening of the upper port c , of the air pump commences, there being a vacuum below the air pump piston as has just been described, the pressure of the exhaust steam acting above the air pump piston forces it down to the bottom of the air pump, changing the position of the cock e , in its descent, to close the lower branch d^2 , and open the upper branch d^1 , of the injection pipe and causing a vacuum to be preserved above the air pump piston during the whole remaining portion of the ascent of the steam piston. The steam admitted to the air pump through the port c , also drives out through the valve g , all the water that may have previously remained in the passage f .

It should be observed that the perforated bottom of the air pump should be so formed that the water will not return through the perforations but will run toward the pas-

sage f^1 , by gravitation, and this passage should be sufficiently capacious to prevent the water rising or accumulating above the perforated bottom.

It will be understood by the foregoing explanation that a portion of the exhaust steam after every stroke of the steam piston operates the air pump during a small portion of the succeeding stroke and is then condensed in the air pump, as in an ordinary condenser to produce a vacuum in front of the steam piston, as well as in the air pump itself.

If ever found in practice to be necessary, the air pump piston may be held stationary at the end of its stroke in either direction by any suitable mechanical means thrown in and out of gear at the proper time.

By this mode of operation, the air pump instead of its being worked at so great an expense of power as to produce an effect equal only to from 4 to 5 pounds per square inch of the steam piston, is rendered automatic, and the full benefit of the vacuum produced in it while acting as the condenser, is obtained on steam piston throughout nearly its whole stroke, and besides this, the exhaust steam, in its action on either side of the air pump piston while there is a vacuum on the other side will produce more power than is required to overcome the friction of the said piston and effect the discharge of the water, and this surplus power may be employed in various ways, for instance in working pumps for raising the water for condensation, in driving blowers, or for many other duties according to the purposes to which the engine is applied, but a portion, if not the whole of such power may be very advantageously employed in helping the crank or cranks of the engine past their centers. The mechanism for transmitting the power of the air pump to the shaft of the engine for the latter purpose may be of various kinds, but I have represented that which I consider the best and which will at least serve as well as any other to illustrate the employment of the power for that purpose. This mechanism I will now proceed to describe. The air pump piston rod is furnished with a cross head P , which works in suitable guides j , j , and which is connected by a rod k , at each end with a forked or double lever Q , whose fulcrum is a rock shaft l , situated directly under and parallel with the crank shaft. This lever is weighted at T , to counterbalance the weight of the air pump piston and piston-rod and other appendages. The cross-head P , is further connected by a rod or rods m , with a lever R , whose fulcrum is a rock shaft n , working in fixed bearings conveniently situated on the upper part of the engine framing, the said lever R , being connected by a pin p , and rod q , with a lever S , whose fulcrum is a rock

shaft *r*, situated directly over and parallel with the crank shaft and at the same distance therefrom as the rock shaft *l*. The rock shafts above mentioned all work in suitably arranged fixed bearings, the bearings of *S*, and *Q*, being so arranged that the axes of their rock shafts or fulcra and the axis of the crank pin *V*, are all in the same plane when the crank pin is on either of its centers 10 or dead points.

The lever *Q*, has a long arm, to which the air pump piston is connected and a shorter arm which has a fork *s*, at its extremity, the length of the said shorter arm being such 15 that a tooth *t*, at the extremity of the crank *E*, is capable of engaging with its fork *s*, and working in combination therewith in a substantially similar manner to the cogs of gearing. The lever *S*, is of the same 20 length as the shorter arm of the lever *Q*, and has a similar fork *s'* at its extremity.

The levers *Q*, *R*, *S*, severally derive from the air pump piston, through the connections above described, an oscillating motion. The 25 lever *R*, is so proportioned that the lever *S*, whose duty it is to move, is caused to make a movement of the same length of sweep as the shorter arm of the lever *Q*; and the length of the lever *S*, and shorter arm of 30 the lever *Q*, are so proportioned to the length of the crank *E*, that either of the two, as the crank passes around with its tooth *t*, in gear with it, will only remain in gear with the crank while the stroke of the air 35 pump is made, and no longer.

It is desirable in applying the surplus power of the air pump piston to act upon the shaft either by the agency of this or any other mechanism that the exhaust of the 40 steam from the cylinder should be permitted to commence just before the piston *F*, arrives at the end of the stroke, as has been a common practice with many engineers. The object of this is to permit the stroke of the 45 air pump piston to take place during the concluding portion of each stroke of the piston *F*, and corresponding portion of its return stroke, in order that the air-pump piston should come in action upon the crank 50 before it arrives on its centers, and remain in action thereon till after it has passed its centers.

With this system of exhausting the steam, the operation of the above described mechanism is as follows. The valve *B*, and its eccentric and working gear, represented in 55 the drawing as set to produce the rotary motion of the crank in the direction of the arrow 1, shown near it, and the mechanism connect with the air pump piston arranged 60 to suit. The crank as represented in black outline as just arriving on its lower center, and the air-pump piston (as has been before mentioned) about to commence its upward 65 stroke. The tooth *t*, of the crank has just

arrived within the fork *s*, of the lever *Q*, which has been waiting in a stationary condition to receive it. The upward stroke of the air pump piston, now commencing, moves the lever *Q*, toward the position 70 shown in red outline, moving its fork *s*, in the direction of the arrow 2, shown near it, and causing the said fork to press against the tooth *t*, and assist the crank in its motion till the said lever and crank both arrive at 75 the position represented in red outline, and the air pump piston has completed its upward stroke, when the tooth *t*, of the crank as moved to a position to pass out of the fork *s*, and leave the latter stationary, while 80 the crank, which has passed its center, proceeds in its revolution.

The air pump piston, in its upward stroke while it operates on the lever *Q*, as above described, moves the lever *S*, from 85 the position shown in black outline to that shown in red, so that its work *s*, may be in readiness to receive the tooth *t*, of the crank at the instant of the commencement of the downward stroke of the air pump piston, 90 which, by causing the said lever to move to the position shown in black outline carries or helps the crank past its upper center in the same manner as the lever *Q*, carried it past the lower one, and then leaves it free 95 to proceed with its revolution. The downward stroke of the air pump piston carries the lever *Q*, to its first specified position, and leaves the fork *s*, in readiness to receive the tooth *t*, of the crank as the latter arrives 100 near its lower center.

Instead of applying the surplus power of the air pump piston to the ordinary crank of the engine through which the steam piston transmits its rotary motion, it may be applied in the same manner to a separate crank or arm specially provided and attached to the shaft for the purpose, or be applied through any suitable means to some other 105 part of the engine.

In the employment of the surplus power of the air pump to aid the crank in its revolution in an engine provided with the means of reversal, the valve *b*, must be so connected with the valve gear which operates the education or induction steam valve or valves as to be capable of reversing the action of the air pump, for either end of the steam cylinder will require to communicate with one or the other end of the air pump, according 115 to the direction in which the crank is to reverse.

My improvement is also capable of use with advantage in high pressure or non-condensing engines. In that case it is only necessary to so arrange a cylinder and piston *K*, with suitable valves, that the exhaust steam shall escape into the atmosphere after operating said piston, instead of being submitted to the water jet. An economical ad- 120 125 130

vantage will ensue without condensation, provided a piston K, is arranged to receive a full stroke from the exhaust steam while the steam piston is just completing and commencing a stroke.

By the term "steam-engine" as employed in this specification, it is my intention to embrace all engines worked by the pressure of a vapor or gaseous body capable of condensation by contact with cold water or liquid, as my invention is applicable to such engines as well as to those actuated by steam.

I do not broadly claim the combination of a condensing cylinder and air-pump, as that is described in the English patent of Pil-brow, 1841, but having described my invention, I claim and desire to secure by Letters Patent.

1. The arrangement of the combined air-pump and condenser piston K, to act inde-

pendently of the walking beam of the engine, so that a portion of the exhaust steam, while the piston F is just completing and commencing a stroke, shall impart a full stroke to the piston K, as herein shown and described.

2. The arrangement and combination of the forked levers Q, S, the crank E, lever R, and piston-rod K', so that by the action of the piston K, the crank E, will be assisted in passing the dead points, but during other portions of the crank movement, the parts above-named will be disconnected from the crank E, all substantially as herein shown and described.

JOHN SUTTON.
